UNITED STATES PATENT OFFICE.

ARCHIBALD W. PAULL, OF WHEELING, WEST VIRGINIA, ASSIGNOR TO WHEELING STAMPING COMPANY, OF WHEELING, WEST VIRGINIA, A CORPORATION OF WEST VIRGINIA.

LANTERN.

1,112,928.

Specification of Letters Patent.

Patented Oct. 6, 1914.

Application filed March 12, 1914. Serial No. 824,216.

To all whom it may concern:

Be it known that I, ARCHIBALD W. PAULL, a citizen of the United States, and a resident of Wheeling, in the county of Ohio and 5 State of West Virginia, have invented a new and useful Improvement in Lanterns, of which the following is a full, clear, and exact description, reference being had to the accompanying drawings, forming part of 10 this specification, in which—

Figure 1 is a side elevation, partially in section, of one form of my improved device attached to one form of tubular lantern; Fig. 2 is a sectional view on the line II—II 15 of Fig. 1; Fig. 3 is a similar view showing the parts in a different position; and Fig. 4 is a similar view showing the parts in still another different position.

My invention relates to an improvement 20 in globe retainer lifting devices, and is designed to provide a device of a cheap, simple and efficient character, adapted to be used in conjunction with the regular globe lifting devices without affecting the operation of 25 said devices. The globe retainer lifting device is also arranged to raise the retainer clear of the globe and to hold it in its raised position to permit the globe to be swung on 30 its usual pivotal connection with the lantern.

The precise nature of my invention will be best understood by reference to the accompanying drawings, which will now be described, it being premised, however, that 35 various changes may be made in the details of construction and general arrangement of the parts without departing from the spirit and scope of my invention, as defined in the appended claims.

Referring to the accompanying drawings, the numeral 2 designates the usual oil well or pot, and extending upwardly from this oil well are the air tubes 3, to the upper ends of which is connected a dome having 45 an outer shell 4 and an inner shell 5. Connected to the top of the dome is the usual top plate 6. Telescopically connected with the dome is a globe retainer having an inner and outer shell 7 and 8, respectively; the inner shell being telescopically connected with the inner shell 5 of the dome, while the outer shell engages a flange on an annular plate 9 connected to an annular flange on the lower end of the outer shell 4 of the dome. Surrounding the inner shell 5 of the dome and

the inner shell 7 of the globe retainer is a coiled spring 10, which engages the dome and the globe retainer for normally holding the globe retainer in its lowermost position.

11 designates the burner, and 12 a globe 60 supporting plate which is pivotally connected to the lantern in any manner, so that it is adapted to swing onto and off from the burner 11. The lantern globe 13 is supported on the plate 12 and is held in position 65 thereon by means of the spring bails 14 connected to the plate 12. The lower end of the globe retainer is flared outwardly, and is shaped to fit the upper end of the globe. It is also reinforced by a wire 15, which is 70 provided with a plurality of loops 16 which engage guide rods 17 secured to the air tubes 3.

Extending through openings in the upper end of the shell 5 of the dome is a rod 18; 75 and journaled in openings in the globe retainer is a crank shaft 19 having an operating lever 20 and a crank 21. This crank 21 is offset at a point intermediate its bearings, and connected to this offset portion and to 80 an offset in the pin 18 is a link 22. The stem of the crank 19 extends laterally to a point adjacent to the air tube 3 at that side, so that the operating handle will bear 85 against the tube when the globe retainer is raised to its uppermost position, as shown in Fig. 2, to hold the retainer in position.

The link 22 is pivotally connected to the rod 18 so that it cannot move longitudinally on the rod, and the lower end thereof is provided with a slot 23 to permit the crank 21 to be moved upwardly therein as hereinafter described. The plate 12 for supporting the globe is pivotally connected at 24 to a crank 25 which is pivotally connected to brackets 26 and 27 connected to the air tubes 3 on each side of the lantern. The bracket 27 is provided with a plurality of stops 28 which are arranged to be engaged by an operating lever 29 on the crank 25 to retain the globe, 100 the plate 12, and the globe retainer in their extreme positions.

When it is desired to raise the globe retainer from the globe, the operating handle 20 is shifted 180 degrees from the position shown in Fig. 1, which will move the parts from the position shown in Fig. 2 to that shown in Fig. 3, and lift the globe retainer 105 clear of the globe 13, so that the globe and plate can be swung on their pivotal con- 110

nection with the crank 25. When the parts are shifted from the position shown in Fig. 2 to that shown in Fig. 3, the crank 21 will pass slightly beyond the center so that the spring 10 will retain the parts in their elevated positions.

If it is desired to raise the globe with the retainer in the usual manner, the operating handle 29 is shifted from the position shown in Fig. 1 to that shown in Fig. 4, so that it will be locked in its lowermost position, as shown in Fig. 4. This raising of the globe together with its retainer slides the crank 21 upwardly in the slot 23 of the link 22. The retainer actuating mechanism is thereby rendered insufficient to further raise the retainer, but remains operative to hold the retainer in its raised position when the lever 25 is actuated to lower the globe away from the retainer. In this position of the parts, the shaft 21 is idle and may be turned by the part 20 without any effect other than to swing the link 22 idly from side to side.

25 The advantages of my invention result from the provision of means for raising and holding the globe retaining device in its elevated position, in combination with a globe lifting device, which is arranged to 30 raise the globe and the globe retaining mechanism independent of the retainer actuating means.

It will be readily understood by those familiar with the art that the actuating mechanism disclosed in this application is 35 applicable to various types of lanterns other than the tubular lantern shown. Also that the globe lifting mechanism at the base of the lantern may be of various forms.

40 I claim:

1. A lantern having a vertically movable globe support, a vertically movable globe retainer, mechanism for raising and lowering said support, globe and retainer, and 45 other mechanism arranged to raise the retainer independent of the globe and the support, said other mechanism having means whereby it operates to hold said retainer in its raised position; substantially as described.

50 2. A lantern having a vertically movable globe retainer, mechanism at the base of the lantern for raising the globe with its retainer, and other mechanism engaging the 55 globe retainer for raising it from the globe,

said other mechanism having means which operate to lock the globe retainer in its raised position; substantially as described.

3. A lantern having a dome, a vertically movable globe retainer, a globe support, a crank pivotally connected to the globe support and to the lantern, a globe mounted on said support, a crank supported by the globe retainer, and a connection between said last mentioned crank and the lantern 65 adapted to raise the globe retainer when the crank is moved in one direction, and also to permit the crank to move with relation thereto when the crank connected to the globe support is manipulated, substantially 70 as described.

4. A lantern having a vertically movable globe support and a vertically movable globe retainer, means for simultaneously actuating the support and the retainer, and 75 a rotary device for actuating the retainer separately from the support; substantially as described.

5. A lantern having a vertically movable globe retainer, lifting mechanism at the base 80 portion of the lantern for raising the globe with its retainer, a lifting crank for the globe retainer, and a swinging fulcrum for said crank, said fulcrum having means for permitting vertical movement of the crank 85 relatively thereto when the globe and its retainer are raised by the base mechanism, substantially as described.

6. A lantern having a vertically movable globe retainer, lifting mechanism at the base 90 portion of the lantern for raising the globe with its retainer, a lifting crank for the globe retainer and journaled therein, and a link swung from the upper portion of the lantern and having a slotted portion 95 engaged by the crank of said shaft, substantially as described.

7. A lantern having a vertically movable globe support and a vertically movable globe retainer, means for simultaneously 100 actuating the support and the retainer, and a rotary device for actuating the retainer separately from the support to lock it in its shifted position; substantially as described.

In testimony whereof, I have hereunto set 105 my hand.

ARCHIBALD W. PAULL.
